UNITED STATES PATENT OFFICE.

SAMUEL W. GILLIN, OF PUEBLO, COLORADO.

HUMIDIFIER.

1,163,402.

Specification of Letters Patent.

Patented Dec. 7, 1915.

Application filed May 29, 1914. Serial No. 841,928.

To all whom it may concern:

Be it known that I, SAMUEL W. GILLIN, a citizen of the United States, residing at Pueblo, in the county of Pueblo and State 5 of Colorado, have invented certain new and useful Improvements in Humidifiers, of which the following is a specification.

My invention relates to apparatus for humidifying the air supplied to the carbureters of internal combustion engines, and is particularly adapted for use in connection with engines employed for propelling 10 automobiles.

Considerable difficulty is experienced in 15 the operation of explosive engines at high altitudes where the air is rarefied and in dry climates due to the lack of moisture in the air.

One of the objects of my invention is to 20 supply moisture to the air drawn into the engine cylinders through the carbureter, converting the moisture into steam to humidify the air and at the same time heat the air leading to the carbureter and the carbureter 25 air passing into the manifold. While this idea is not broadly new, my invention has greatly increased the efficiency of the apparatus for accomplishing this purpose and has rendered the method of humidifying 30 the air more uniform and certain in operation.

In the accompanying drawings which illustrate the preferred form of my invention, Figure 1, is a side elevation of an apparatus embodying my invention, showing the manner of connecting it to the carbureter and manifold of an explosive engine; Fig. 2 is a longitudinal section of one form of my humidifier and the heating jacket surrounding 35 a portion of the engine manifold; Fig. 3 is a section on the line 3—3 of Fig. 2; Fig. 4 is a modified form of humidifier with an attachment for conducting the water thereto by capillary attraction; Fig. 5 is a cross-section on the line 5—5 of Fig. 4; Fig. 6 is an end view of Fig. 4, looking in the direction of the arrow 6; Fig. 7, is a perspective view, partly broken away of another form 40 of my humidifier; Fig. 8 is a cross-section of Fig. 7 on the line 8—8; Fig. 9 is a longitudinal section thereof on the line 9—9 of Fig. 8; Fig. 10 is a longitudinal section of a further modification of my humidifier; and Fig. 11 is a cross-section on the line 11—11 45 of Fig. 10.

The form of humidifier shown in Figs.

1 to 3, in which the air is humidified and heated, comprises a jacket 1, which may be formed in two parts so that it may be placed over the engine exhaust pipe 4, the parts 60 being secured together by clamping bands 5. The portion of the exhaust pipe inclosed by the jacket is incased in a cylinder 7, made of porous material and which may also be formed of two semi-cylindrical portions. 65 The space between the cylinder and the jacket forms a humidifying chamber 9. During operation moisture is constantly supplied to the cylinder 7 through a pipe 10 preferably branched as shown, and connected to a 70 water-supply tank 12, which may be conveniently located so that the valve stem 13 may project through the dash-board 14 with easy access of the operator.

A pipe 16, leads from the chamber 9 to 75 a heating jacket 18, surrounding the base of the manifold 20, and from the jacket 18, a pipe 21, leads to the air intake 23 of the carbureter 25, which may be provided with the usual float chamber 27, connected with 80 the fuel supply pipe 28, and with a priming device controlled by a rod 30. The manifold is provided with the usual controlling valve of the butterfly type, the shaft 29 of which carries the lever 31, and is operated by a 85 rod 32, leading to the dash-board. The humid air pipe 16 is provided with a valve 17, having a controlling rod leading to the dash-board.

The operation will be understood from 90 the foregoing description of the apparatus.

The air which is drawn through the carbureter enters the chamber 9 through an opening 6 in the end of the jacket 1 and becomes thoroughly vaporized as it passes 95 over the steam-emitting porous cylinder 7, the whole chamber 9 being constantly filled with steam. The pores of the cylinder 7 are constantly replenished with moisture from the tank 12, and as the interior surface of 100 the cylinder is in intimate contact with the hot exhaust pipe 4, the moisture is readily transformed into steam. Inasmuch as the porous body extends substantially throughout the length of the jacket, the steam is 105 very uniformly distributed throughout the chamber. It will be evident that the numerous pores distributed throughout the entire body of the cylinder and completely surrounding the hot exhaust pipe, insures a far more constant supply and uniform distribution 110 of vapor than would be the case if the

moisture were supplied merely by dropping water upon the exhaust pipe. In so far as I am aware I am the first to provide a means for supplying a constant amount of vapor and uniformly distributing it through the vaporizing chamber, thereby insuring a uniform product.

Instead of supplying the water by gravity as in Fig. 1 I may supply it by capillary attraction through a wicking 35, as illustrated in Fig. 4. The wicking extends from the water supply tank 37, through the tube or pipe 38 into the chamber within the humidifier casing 1^a which is filled with wicking, 15 felt or other moisture-absorbing porous material 35^a. The porous material 35^a is kept constantly wet by the capillary action of the wicking, so that it presents an extended saturated surface which is readily converted 20 into steam and vapor by the heat of the exhaust pipe 4. The air to be humidified enters through the openings 40, and passes out through the pipe 16^a leading to the jacket 18, from whence it passes to the carbureter. 25 In Figs. 7 and 8 I have shown the humidifier casing 1^c having its bottom wall in the form of a saddle which fits snugly over the exhaust pipe. The casing is partly filled with water which is constantly passing off 30 in the form of vapor and steam and permeates the porous felt partition 42. The space above the felt partition and the top of the casing forms a vaporizing chamber 44. The air enters through the screen 40^a, is 35 thoroughly humidified as it passes over the wet felt partition 42, and commingles with the steam and vapors which fill the chamber, passing out through the outlet 16^a leading to the carbureter. 40 In Figs. 10 and 11 I have shown another form of humidifier which is very compact and efficient. Embedded in the inner porous member 48, are water supply pipes 49, connected to any suitable tank. Surrounding 45 the member 48, is another porous absorbent member 50. In order that the air passing through the humidifier may pass over a large surface of the moisture laden porous members, I space the inner member from the exhaust pipe by means of protuberances 53 and in the outer surface of the outer porous member, I form longitudinal channels or grooves 55, so that the air entering through the openings 40 may divide through the inner passages 54 and the outer chan-

nels 55, thereby passing upon both sides of the moisture and steam laden porous members.

In all forms of my invention, the air passing through the humidifier comes into intimate contact with an extended moisture-laden and steaming porous surface thereby causing the air to become thoroughly impregnated with moisture. Inasmuch as the pores of the porous body are constantly supplied with water from the supply tank and these water-filled pores are constantly subjected to the heat from the inclosed exhaust pipe the vaporizing action is uniform and constant while if it were supplied by causing 70 water to drop upon the hot pipe there would be intermittent evolutions of steam and the moisture in the air passing through the casing would be very uneven, causing a corresponding variation in the action of the engine. 75

I have described in detail the construction illustrated in the accompanying drawings for the purpose of disclosing embodiments of my invention, but it will be evident to 80 those skilled in this art that changes may be made therein within the scope of my claims and without departing from the scope of my invention.

I claim:—

1. A humidifier comprising an annular casing adapted to surround a heated member, said casing having inlet and outlet ports, a porous body within said casing and arranged to form one wall of an unobstructed channel connecting the inlet and outlet ports, and means for supplying water to the said porous body. 85

2. A humidifier adapted to receive heat by contact with a heated body, comprising 90 an annular cellular absorbent body, an impervious tubular casing enveloping said body and having inlet and outlet ports connected by an unobstructed channel, one of the circular walls of said annular body constituting a wall of said channel, a water supply, and a conduit connecting said supply with said body. 100

In testimony whereof I affix my signature in presence of two witnesses.

SAMUEL W. GILLIN.
